A. BOHY.
AGITATOR FOR WASHING MACHINES.
APPLICATION FILED JULY 6, 1918.

1,286,923.

Patented Dec. 10, 1918.

UNITED STATES PATENT OFFICE.

ALFRED BOHY, OF ALBIA, IOWA.

AGITATOR FOR WASHING-MACHINES.

1,286,923.

Specification of Letters Patent. Patented Dec. 10, 1918.

Original application filed May 8, 1918, Serial No. 233,299. Divided and this application filed July 6, 1918.
Serial No. 243,640.

To all whom it may concern:

Be it known that I, ALFRED BOHY, a citizen of the United States, residing at Albion, in the county of Monroe and State of Iowa, have invented certain new and useful Improvements in Agitators for Washing-Machines, of which the following is a specification, reference being had to the accompanying drawings.

10 This invention relates to agitators for washing machines, and has for its primary object to provide an agitating mechanism operated by suitable gearing, whereby the clothes or other articles arranged in the 15 cleansing fluid contained in the tub or receptacle will be thoroughly agitated.

It is also one of the more particular objects of the invention to provide an agitator and an operative connection between the 20 same and its actuating shaft which affords a limited relative axial movement of the agitator in the rotation or oscillation thereof, whereby the cleansing fluid will be caused to permeate all parts of the fabric articles 25 contained in the tub or receptacle.

It is also an important object of the invention to provide improved means for mounting the agitator, which is of such construction that frictional contact between 30 metal parts in the relative movement of the agitator is avoided, whereby wear of the metal surfaces, resulting in the formation of rust, will be obviated.

It is also a further general object of the 35 invention to improve and simplify the construction of agitators for washing machines whereby the same will be rendered strong and durable, efficient and serviceable in practical use, and capable of manufacture at relatively small cost.

With the above and other objects in view, the invention consists in the improved construction, combination and relative arrangement of the several parts as will be herein- 45 after more fully described, subsequently claimed and illustrated in the accompanying drawing in which similar reference characters designate corresponding parts throughout the several views, and wherein:—

50 Figure 1 is a side elevation of my im-

proved agitator, showing the same operatively mounted in the tub or receptacle;

Fig. 2 is an enlarged horizontal section taken on the line 2—2 of Fig. 1;

Fig. 3 is a section taken on the line 3—3 of 55 Fig. 2; and

Fig. 4 is a section taken on the line 4—4 of Fig. 2.

The invention forming the subject matter of the present application constitutes a division of my prior application for patent, Serial No. 233,299, filed May 8, 1918. Therefore, the operating gearing, which is fully shown and described in said application, will not be herein described in detail. It will suffice to state that the agitator is arranged 60 in the usual manner within a clothes receiving tub or receptacle 5 and is actuated by means of a gear driven shaft 10 centrally mounted in the top or cover of said receptacle. 65

To the lower end of the actuating shaft 10, a yoke-shaped casting 41 is securely fixed by means of the pin or bolt 42 extending transversely through said shaft and a sleeve 75 centrally formed on the casting. The parallel depending arms 43 of this casting are provided with portions of substantially semi-circular form in cross section, as shown at 43', which terminate at one of their ends 80 in the inwardly projecting, horizontal shoulders 44. Each arm 43 also has a cylindrical end portion 55 extending longitudinally from the shoulder 44. The purpose of this specific construction of the yoke arms will 85 be hereinafter more fully explained.

The agitator proper is of cruciform shape in plan and consists of two intersecting wood bars 45 having their central portions halved for interlocking engagement in the 90 usual and well known manner. Each of these bars 45 is provided at its ends with angular lugs or extensions 46, preferably of cylindrical form and slightly inclined in an outward direction. One of the bars 45 is 95 provided at points equi-distantly spaced from its center with the circular openings 47 extending vertically therethrough. These openings are of sufficient diameter to permit of the passage of the inwardly projecting 100

shoulders 44 on the arms of the casting 41 through the same. The upper face of this agitator bar 45 is formed with a longitudinally extending recess or countersink 48 to receive a stop bar 49, which is also constructed of wood. The ends of this bar project over the respective openings 47 and have rounded or convex end edges, indicated at 50, contacting with the inner concave faces 10 of the casting arms 43. Such contact, however, is not sufficiently tight to prevent the free vertical sliding movement of the agitator with respect to the arms of the casting. The bar 49 is retained by means of a metal 15 plate 51 which is disposed at right angles to the bar 49 and extends longitudinally upon the other of the agitator bars 45. This plate at its ends is formed with flanges 52 which are seated in grooves provided in the surface 20 of the agitator bar. The agitator bars, 45, the bar 49 and the plate 51 are all centrally formed with coinciding openings to receive the fastening bolt, 53, whereby the several parts may be rigidly secured together and held against relative movement by the 25 clamping nut 54 threaded on the lower end of said bolt.

From the foregoing description, taken in connection with the accompanying drawings, the construction and manner of operation of my improved agitator will be clearly and fully understood. In the actuation of the shaft 10, a rotary, oscillating motion is imparted to the agitator. In the alternate 30 rotation of the agitator in opposite directions it will likewise move vertically upon the arms of the casting 41, the downward movement of the agitator by gravity to its normal position being limited by the engagement of the ends of the stop bar 49 with the shoulders 44 on the arms of the casting, and its upward movement being limited by the engagement of the agitator with the horizontal bar of the casting. In 35 this vertical movement of the agitator, the angular lugs 46 thereof engaging the clothes causes the cleansing fluid to thoroughly permeate all portions of the fabric. The solid cylindrical end portions 55 of the arms 43 serve to prevent relative lateral movement 40 of the agitator bars and provide reinforcements for the casting arms, thereby decreasing wear upon the walls of the openings through the agitator bar and more effectively holding the agitator stiff or rigid. The several parts of the device are of simple 45 form, strong and durable in their construction, and not liable to get out of order. The surfaces of the casting are preferably 50 galvanized or otherwise finished to prevent rusting and by eliminating frictional wearing contact between metal parts in the vertical movement of the agitator, these metal surfaces will not become worn. Thus, the

possibility of rusting of the metal parts, 65 with consequent injury to the clothes, is obviated. I have herein illustrated one particular form of the agitator bars and the supporting casting therefor, but it will be understood that in practice, it may be found 70 desirable to materially vary the relative proportions of these parts. The several other elements of the device are likewise susceptible of considerable modification in their form, construction and relative arrangement, and it is, therefore, to be understood 75 that I reserve the privilege of adopting all such legitimate changes as may be fairly embodied within the spirit and scope of the invention as claimed. 80

I claim:—

1. In a washing machine mechanism, an agitator shaft, an agitator, a member fixed to one end of said shaft and having spaced longitudinally projecting arms, said agitator being provided with spaced openings to receive the arms of said member, each of said arms having a stop lug, and a bar fixed to the agitator to engage said lugs and limit the longitudinal movement of the agitator upon the arms in one direction. 85

2. In a washing machine mechanism, an agitator shaft, an agitator, a member fixed to one end of said shaft and having spaced longitudinally projecting arms, said agitator being provided with spaced openings to receive the arms of said member, each of said arms having a stop lug, a bar fixed to the agitator and projecting over said openings, the ends of the bar having sliding contact with the arms of said casting and adapted to engage said lugs to limit the longitudinal movement of the agitator in one direction. 95

3. In a washing machine mechanism, an agitator shaft, a member fixed upon one end of said shaft and having spaced longitudinally extending arms provided with lugs, an agitator consisting of intersecting bars, one of said bars having openings therein to receive said arms, a stop bar countersunk in said agitator bar and projecting over the openings therein, the ends of said bar being adapted to engage said lugs and limit longitudinal movement of the agitator in one direction on said arms, a plate extending longitudinally upon the other of the agitator bars and over said stop bar, and a common means for securing the agitator bars, the stop bar and said plate against relative movement. 105

4. In a washing machine mechanism, an agitator shaft, a member fixed to one end of said shaft and having spaced channel-shaped arms terminating in cylindrical extensions affording a stop shoulder on each arm, an agitator provided with spaced openings to receive the arms of said mem- 110 115 120 125

ber, said agitator having means to engage the stop shoulders and limit the gravity movement of the agitator to its normal position upon the arms, said cylindrical ends of 5 the arms being disposed within said openings in the normal position of the agitator.

In testimony whereof I hereunto affix my signature in the presence of two witnesses.

ALFRED BOHY.
